John J. Phelan.
By Albert A. Barker, Atty.

UNITED STATES PATENT OFFICE.

JOHN J. PHELAN, OF WORCESTER, MASSACHUSETTS.

CLEAN-OUT FOR SOIL-PIPES.

No. 838,642.

Specification of Letters Patent.

Patented Dec. 18, 1906.

Application filed April 8, 1905. Serial No. 254,511.

To all whom it may concern:

Be it known that I, JOHN J. PHELAN, of Worcester, in the county of Worcester and State of Massachusetts, have invented certain new and useful Improvements in Clean-Outs for Soil-Pipes, of which the following is a specification.

Figure 1 represents a central longitudinal section through a soil-pipe fitting with my improved clean-out applied thereto. Fig. 2 is a transverse section through said clean-out, taken at the point indicated by line *a*, Fig. 1. Fig. 3 is a central longitudinal section through said clean-out and a transverse section through the pipe to which it is applied, taken at the point indicated by line *b*, Fig. 1. Figs. 4 and 5 are a side and plan view, respectively, of an internally-threaded ring employed in the construction of my said improved clean-out. Fig. 6 represents a central section through the various parts of the clean-out, similar to the section shown in Fig. 1, with temporary screw-plug fitted therein to confine the molten metal within proper limits in the operation of pouring to produce the desired lead seal and seat for the usual permanent screw-plug, as will be hereinafter more fully described. Figs. 7 and 8 are a plan and side view, respectively, of a cup used in the clean-out, as and for the purpose also hereinafter described; and Fig. 9 shows a side view of a modified construction of the internally-threaded ring previously referred to.

My invention relates principally to clean-out fittings for soil-pipes employed for sewerage and drainage systems.

The object thereof is to provide a clean-out of simple inexpensive construction, whereby a tight fitting may be produced without the use of leather, rubber, or other similar packings.

Said invention consists in combining with the clean-out hub, having an inwardly-flaring annular recess larger at the inner than the outer end, also having an annular beveled rim extending into said recess around and next to the central opening of the hub, an internally-threaded ring fitted longitudinally in said recess of the hub just outside of said annular beveled rim and having openings through its inner end at intervals around its circumference, an exteriorly-threaded plug fitted in said laterally-threaded ring, the seat for said plug formed by pouring molten metal into

the device, which also forms the packing 55 therefor, and a cup fitted in the central opening of the hub, having an open outer end and a closed inner end, the latter conforming to the shape of the interior of the pipe, as will be hereinafter more fully set forth.

60

To enable others to better understand the nature and purpose of my invention, I will now proceed to describe it more in detail, with reference to the accompanying drawings.

In said drawings, *A* represents a soil-pipe 65 fitting with my improved clean-out *B* formed thereon, said fitting being shown calked to sections of pipes *C D* at each end. Said clean-out is constructed in the following manner: The hub *c* thereof is provided with a recess *d*, 70 having inwardly-flaring sides *e*, or, in other words, made larger at the inner than the outer end, the purpose of which will be hereinafter described. Upon said hub and projecting into said recess is also formed an annular rim 75 *f* next to the central opening *g* of the hub, said rim being beveled on its outer edge *f'*, for the purpose also hereinafter described. Just outside of said rim *f* is fitted in recess *d* a ring 80 *h*, having internal threads *h'* formed at or near its outer end and provided with a series of openings *h*² at or near its inner end around its circumference. A plug *i*, having internal threads, is fitted in the internally-threaded ring *h*. Said plug when screwed into position 85 fits against a soft-metal seat *j*, preferably lead, formed by pouring molten metal into the recess *d* at the points indicated by the arrows in Fig. 6, which molten metal, passing through the openings *h*² in the ring *h*, fills the annular 90 chamber *k* inside of said ring between the rim *f* and inner side of the screw-plug *i*, thus not only forming said seat *j*, but also forming the lead packing *l* around the internally-threaded ring *h*. In forming said seat and packing a 95 special temporary screw-plug *m* (see Fig. 6) is employed, having a central core *m'* extending into the central opening *g* of the hub to keep the metal from flowing into said central opening, said screw-plug *m*, aside from its core *m'*, being substantially like the usual permanent screw-plug *i* first described.

After the molten metal has been poured to form the seat and packing as aforesaid and said metal has hardened by cooling the temporary screw-plug is removed, thereby forming the clean-out ready to receive the cup *n* and usual screw-plug *i*. As will be observed

100

105

by reference to the drawings, the rim *f* being beveled upon the outside next to the ring *h* permits the metal to flow freely from the outer recess of the hub into the annular chamber *k*, which forms the seat *j* of the clean-out. The cup *n* is made to fit the central opening of the hub. It is open at its outer end and closed at its inner end, said inner end being shaped to conform to the shape 10 of the opening in the pipe, as is shown in the drawings. The outer open end of said cup is provided with an external annular rim or flange *o*, which fits over the inner edge of seat *j*, and is thereby held from inward longitudinal 15 displacement, the screw-plug *i* when fitted in position serving to hold it in the opposite direction. It is essential that the cup be held from turning in order to keep it in proper position in relation to the opening in 20 the pipe. This may in practice be done in various ways, and I therefore do not limit myself to any special way. In this instance I accomplish said result by forming ears *p p* on opposite sides of the cup, which fit in correspondingly-shaped slots formed in the hub 25 and seat of the clean-out, as is best shown in Fig. 2. The inner edge of the ring *h* may be perforated with openings of various shapes by segment-openings *h²*, as is shown in Fig. 4, 30 circular openings *r*, as shown in Fig. 9, or any other desired shapes adapted for the purpose.

By making the recess *d* in the hub with inwardly-flaring sides, as shown and described, 35 it is obvious that the soft-metal packing may be held securely in place from being forced out by the pressure exerted in screwing the plug *i* in position against its seat. In fact, the greater the pressure exerted the more 40 firmly will the packing be held by pressure against said beveled sides, this feature of my invention also by said outward pressure serving to make tighter sealed joints between the parts. Since it is thought that said feature of making the sides of the recess in the 45 hub flaring inward is new in piping for the purpose described, I reserve the right to protection thereon in connection with any pipe-joint where soft-metal or other similar packing is used.

My improved clean-out is designed for use not only in a straight line of piping, as is shown in the drawings, but also for end clean-outs on straight runs, Y branches, or 55 any points where such a clean-out is desirable. I prefer to use the cup *n*; but since it

is not an essential feature to my invention I reserve the right to use the same or not, as desired.

The feature of making the interior sides of the hub flaring inward, as described, is of special importance for the reason stated of insuring the retention of the packing from displacement and thereby, also, insuring a permanent tight joint. I believe said feature to be new in soil-pipe fittings, and I therefore reserve the right to apply the same to other pipe-fittings than clean-outs.

Having now described my invention, what I claim therein as new, and desire to secure by Letters Patent, is—

1. A clean-out for piping, comprising the hub, having an inwardly-flaring, annular recess, larger at the inner than the outer end, also having an annular beveled rim extending into said recess around and next to the central opening of the hub, in combination with an internally-threaded ring, fitted longitudinally in the recess of the hub, just outside of said annular beveled rim, and having a series of openings through its inner end, an externally-threaded plug fitted in said internally-threaded ring, and the soft-metal seat and packing formed by pouring molten metal into the device, substantially as and for the purpose set forth.

2. A clean-out for piping, comprising the hub, having an inwardly-flaring, annular recess, larger at the inner than the outer end, also having an annular beveled rim extending into said recess around and next to the central opening of the hub, in combination with an internally-threaded ring, fitted longitudinally in the recess of the hub just outside of said annular beveled rim, and having a series of openings through its inner end, an externally-threaded plug, fitted in said internally-threaded ring, the soft-metal seat and packing formed by pouring molten metal into the device, and the cup fitted in the central opening of the clean-out, having a closed inner end corresponding in shape to the interior of the pipe, and having means for preventing it from turning, substantially as and for the purpose set forth.

In testimony whereof I have affixed my signature in presence of two witnesses.

JOHN J. PHELAN.
